UNITED STATES PATENT OFFICE.

GEORGE A. JESSOP, OF YORK, PENNSYLVANIA, ASSIGNOR TO S. MORGAN SMITH COMPANY, INC., OF YORK, PENNSYLVANIA, A CORPORATION OF PENNSYLVANIA.

DRAFT TUBE.

Application filed June 17, 1927. Serial No. 199,530.

This invention relates to draft tubes, and particularly to the elbow type formed of concrete or other analogous material or in some instances formed of metal. The present invention embodies an improvement of the structure disclosed by my pending application filed March 11, 1925, Serial No. 14,850. The same obvious structural advantages in operation in draft tube structure are sought and desired to be maintained in the present structure as in my original improved elbow draft tube disclosed by the aforesaid application, the material variation in the structure of the outlet leg of the tube and a more efficient result in operation being the distinguishing features of the present improvement. It has been discovered that there is a higher velocity at the bottom and outside edges of the tube than at the top center from points starting well into the down stream curvature of the elbow and continuing to the outlet of the tube. This variation in velocity begins shortly after the tube starts to bend, and becomes a maximum at or near the end of the elbow and then decreases towards the outlet. In order to obtain the best possible efficiency in a draft tube of the elbow, or any other type, it has been found necessary to so form the tube that the water remains in full flowing contact with all surfaces of the tube which is accomplished to a very material extent by my novel curvature of the elbow in this class of elbow draft tubes, and as specified in my aforesaid application. In accordance with the features of this improvement a more efficient and complete or full flowing contact with the surface of the outlet leg of the tube is obtained by filling in the top of the tube at the center along the horizontal leg and for a distance upwardly into the down-stream portion of the elbow top curve, and thereby overcome the formation in the tube of a comparatively dead space at the center and top of the horizontal leg or outlet portion of the tube, and thereby secure a more even distribution of water in all parts of the tube. As the water flows downwardly through the tube from the entrance and is gradually turned from a vertical direction by the upstream curvature of the elbow, there is a natural spreading effect

which increases and becomes more noticeable at what may be termed each section of the elbow organization. At the beginning of the upstream curvature of the elbow section the spreading effect is slight and becomes greater in the successive portions or sections thereof until it reaches its maximum at or near the final section where the elbow merges into the outlet or horizontal leg of the draft tube. The velocities in these tubes, particularly when used for turbines under very large heads, are quite high, and the spreading action is therefore quite rapid and causes a large portion of the water to pass to the outside curved periphery of the tube at the final sections of the elbow or near the terminal of the latter situated adjacent to the horizontal leg of the tube outlet. The water at the outside of the tube is therefore assuming a spiral motion but flows forwardly along the tube at a more rapid rate than its rate of spiral revolution, the spiral movement of the water being insufficient to force or throw the water to the center of the tube and permitting a void to be formed at the center of the tube, which should be filled or rectified by change of shape of the tube to eliminate eddies and partial voids.

The general operation of the present tube within the length of the curvature complete is the same as that disclosed in my pending application above noted, but in the improved structure there is a modification of structure to attain a more satisfactory and complete operation and thereby overcome the slight disadvantages present in my prior structure. The improvement as set forth in this application is particularly advantageous where it is desirable to install elbow draft tubes of comparatively small vertical height and short horizontal length. The improved elbow has the same curvature on the upstream surface and the same shape at the bottom of the horizontal leg, and it has the same construction and easement curves on the downstream, or upper side of the elbow bend, throughout the bend at the outside portions. The center portion of the upper side of the elbow bend, near the end of this part of the tube, is modified by filling in, or reducing the area by means of an obtuse triangular pad or inverted arch,

with, preferably approximately straight sides. The height or extent of this pad is a maximum at the center of the tube and decreases to nothing at the sides or where it 5 joins the fillets at the upper outside portions of the elbow bend. In some cases where this improvement is used, it will be necessary to make the outside portions of the elbow bend, near its termination, of a greater vertical extent than would be used with a tube 10 constructed according to my co-pending application, Serial No. 14,850, in order to provide a draft tube with an increasing area in the direction of flow from the inlet to the 15 outlet of the tube, or, at the limit, to provide a draft tube that does not decrease in area at or near the end of the elbow bend. In some cases, it may be desirable to make the tube with a constant area for a com- 20 paratively short distance, in the vicinity of the end of the elbow bend. It is not intended that the improved draft tube be limited to any particular rate of increase of area or to any particular rate of decrease of velocity. Further, in the present improved 25 structure, wherever it is possible, this inverted arch roof portion embodies a straight line construction and the curved, or circular, sides of the prior structure are replaced 30 with vertical sides, sometimes with straight fillets at the farthest possible upstream section of the tube consistent with satisfactory results. This simplifies and cheapens the work required to construct the tubes, 35 whether made of concrete, metal or other material.

The present object of this invention therefore, is the provision of an inverted arch roof or top portion for the horizontal leg 40 of the draft tube to obtain a more uniform velocity at the outlet of the tube, and to secure a uniformity of flow of water with the greatest possible reduction in velocity from the entrance of the draft tube to the outlet 45 of the tube, and whereby the formation of a dead space at the center and top of the horizontal leg is entirely avoided and a more even distribution of the water over the remaining passage is obtained, thus over- 50 coming the disadvantage of having the water break away in the top or downstream curve of the elbow.

The present invention consists essentially in the preferred general construction and 55 arrangement of parts which will be more fully hereinafter described and claimed.

The accompanying drawings illustrate the improved draft tube formed of concrete or analogous cementitious material, but it 60 will be understood that the same essential features of invention may be included in a metal or sheet steel draft tube.

In the drawing:—

Fig. 1 is a transverse vertical section 65 through a draft tube embodying the im-

proved features of the invention, the difference in construction being illustrated at the outlet or horizontal leg of the draft tube, and indicated by a dotted line.

The numeral 5 designates a concrete or 90 other cementitious structure in which the improved tube is suitably formed, the latter comprising an upper inlet extremity 6 over which the runner or wheel is adapted to be mounted in the usual manner. The concrete or other analogous structure 5 may be 95 continued upwardly any suitable distance to serve as a base support for the installation of the remaining part of a turbine or other water power organization, and also 100 for the purpose of supporting a power house in which the turbine unit or units are disposed. The upper member 7 of the improved draft tube is shown as composed of sheet metal down to the point 8, the remaining part of the draft tube being shaped in the concrete or other material. It will be understood that the upper member 7 of the draft tube, which may be specified as the 105 "inlet member" may in some instances be 110 constructed or shaped in the concrete. This upper inlet member 7 to a point a short distance below the plane of section 2. 2. is concentric with relation to the axial line 9^a which is also the vertical axis of the runner 115 or wheel and the turbine shaft. The upper inlet member 7 may be slightly bowled and regularly flares in a downward direction as shown or it may have a straight taper or flare. At a comparatively short distance 120 below the plane or section on the line 2. 2. and as indicated by the plane of section 3. 3. Fig. 3, the draft tube begins to assume an elliptical contour, and this configuration increases gradually in the present instance 125 through to the plane of the section 6. 6., as indicated by Figs. 3 to 6 inclusive. In order to arrive at this construction, the curve 11 of the upstream or lower side of 130 the elbow begins prior to the curve 12 of

Fig. 1 is a transverse vertical section 65 through a draft tube embodying the im-

the downstream or forward upper wall of the draft tube elbow. The rear or upstream curve 11 comes from the vertical to the horizontal in an arc with a practically constant radius, or in other words, with a constant curvature. The curvature of the downstream or upper face of the elbow starts at a materially lower elevation than the upstream curve 11 when considering a vertical 5 tube construction only. In other words, the curvature 12 of the downstream face of the elbow in the downstream direction starts much later than the curvature 11 of the upstream face. This downstream curve 12 10 of the upstream face is an easement curve, that is, at the beginning thereof there is a long radius of curvature and this radius is gradually decreased and becomes a minimum at or near the end of the curve, as at 15 9, for the outside portions of the tube and, as at 13, for the central portion of the tube. In a vertical setting the points are about 20 at the horizontal. From the point of the plane of the section 7. 7. to the point 13 25 or end of the easement curve there is a modification of structure in the present improved invention relatively to that disclosed in my prior application heretofore noted for the purpose of assisting the water to remain 30 a more perfect full flowing contact with the downstream or upper portion of the elbow of the draft tube, and assist in maintaining a practically equal velocity of water at a given section of the draft tube. The main- 35 tainance of an equal velocity at all points in a given section of a draft tube, said section being taken approximately at right angles to the longitudinal center line, is necessary in order to maintain smooth flow 40 and high efficiency in the tube. Again, for the purpose of illustration, let it be assumed that the tube is divided into three distinct parts. The first part is the vertical section 45 or inlet member 7 with a straight vertical center line immediately below the runner. The sections at this inlet part or member of the tube are true, or approximately true circles, and for convenience of description the words "breadth" and "width" will be 50 applied to the different sections of the tube, the "breadth" being intended to mean the distance between the walls of the tube as cut by a plane passing through a longitudinal center line thereof, and by "width" is 55 meant the distances between the walls of the tube as measured at right angles to the foregoing plane, each measurement passing through the longitudinal center line of the tube. 60 The second part of the tube is the curve or elbow section 10. The breadth of the tube is a maximum at approximately the end of the first part, and at approximately the beginning of the second part or section or 65 elbow 10. The breadth of the second part or elbow member 10 relatively decreases from its maximum at the entrance of this second part or section to its minimum at or near the end of the elbow, as at 9 and 13. In other words, the upstream or lower face 70 of the draft tube defined by the curve 11 approaches and gets nearer to the downstream or upper face of the draft tube defined by the curve 12. At the same time the width or lateral extent of the draft tube is 75 increased all along the bend or elbow section 10, and this increase is such that the area of the tube is constantly increasing, so that the velocity of the water in the tube is 80 constantly decreasing, or the velocity head is constantly being converted into pressure head. The reduction in the breadth of the tube from the beginning of the upper end of the second section or part or elbow 10 is accomplished by making a curvature of the up- 85 stream and downstream faces of the tube, or the lower and upper sides of the tube, in the curvature heretofore specified, and further because the curvature of the downstream or upper face or side is started at a 90 considerably lower point or later than the curvature of the upstream or lower face. The third part of the sectional tube is the horizontal leg 15 which serves as the outlet. Both the breadth and width of this leg may 95 increase gradually, but it is unnecessary that both increase, in view of the fact that one dimension, for instance, the vertical extent of the leg, could remain constant and even be decreased, provided the width or lateral 100 extent of the tube be increased a sufficient degree to maintain the continuously increasing area as the water approaches nearer and nearer the outlet end 16. As hereinbefore indicated, from the entrance of the improved 105 tube to the outlet end thereof the area is continuously increasing and therefore the velocity of the water is continuously decreasing. 110 The present improvement, in view of my prior structure, preserves in the main the same structural condition just enumerated with structural modification or changes in the upper part of the outlet leg or section 15 and a continuance of the same change into 115 the downstream part of the elbow as far upwardly as about the plane of the section indicated by the line 7. 7. shown by Figure 1, and which consists in directing the curve 17 at the center of the downstream easement 120 portion of the tube with a longer series of radii than the similar easement curve represented by the right hand end of the dotted line 17^a, in the construction of the elbow de- 125 scribed by my aforesaid application at the downstream or upper portion of the said elbow and than the similar curve used in the construction of the present elbow at the outside portions of the elbow bend, the said curve 17 continuing to depart regularly from 130

the curve 17^a until it reaches about the point 13 where it gradually merges into a flattened top portion 18 of the outlet leg 15 which is substantially below the line 17^a which line 5 indicates the height of the central portion of the top of the draft tube outlet leg as shown in my said prior application. At about this point 13 is the rear terminal of a supporting pier 19 which is located in the center of the horizontal outlet leg 15 and continues fully to the outlet end 16 of the leg. As indicated by the cross sections, in Figures 9, 10 and 11, the flat top converges from opposite sides, as at 20, Figure 9, 21, 10 Figure 10, and 22, Figure 11, equally towards the center of the leg of the tube, the section 15 9 being adjacent to the lower terminal of the curve 17, and the said inward convergence, as at 20, at opposite side portions of the tube 20 in the lower extremity of the elbow starts a little to the rear of the plane of the cross section, as illustrated by Figure 9 or nearly as far back inwardly and upwardly as the plane of the section 7, and gradually the 25 convergence increases in angularity or has a greater dip towards the center from opposite sides, as illustrated by Figures 10 and 11. As shown by Figure 9, the opposite sides of the elbow, as at 23, are curved to form 30 fillets where these sides join the top and bottom walls, but this curvature gradually merges or is changed into a more nearly straight or vertical side structure, as at 24, Figures 10 and 11, and the angular corners 35 formed by the intersections of the outer extremities of the upwardly inwardly converging portions 21 and 22 as shown by Figures 10 and 11 and the bottom 25 are filled by fillets 26 throughout the whole length of the 40 leg 15. Hence the outlet leg 15 of this improved draft tube as compared to my prior improved structure is filled in the center of its top portion to the depth shown between lines 17^a and 18 and thus materially aids in 45 overcoming the tendency of the water to break away from the top or downstream curve of the elbow at the plane of the sections 8 and 9, and eliminating from the tube the comparatively dead space at the center 50 and top of the horizontal leg 15 and obtaining a more even distribution of the water, over the remaining passage and also avoiding any tendency to spiral motion of the water along the side portions of the leg, the 55 latter having at the top thereof a straight line construction of inverted arch contour. This improved construction not only results in a more satisfactory full flowing contact of the water at the opposite sides of the leg 60 without any tendency towards spiral movement and a consequent elimination of eddy formation and void spaces, but also simplifies and cheapens the form work required to cast these draft tubes in the concrete. This 65 improved structure of elbow draft tube

produces full flowing water contact with all surfaces throughout the length of the tube, and the water is gradually decelerated towards the outlet end 16 of the tube, and is finally discharged into the tailrace. 70

What is claimed as new is:—

1. A draft tube having an inlet extremity concentric with relation to a central axis and continuing into an elbow which is gradually decreased in breadth from the upstream towards the downstream portion thereof by an upstream, practically constant radius curve and a downstream easement curve, the draft tube being increased in width and terminating in an outlet extremity having a top portion which is lower at its center than at its sides. 75

2. A draft tube having an inlet extremity concentric with relation to a central axis and continuing into an elbow which is gradually decreased in breadth from the upstream towards the downstream portion thereof by means of an upstream, practically constant radius curve and a downstream easement curve and proportionately laterally increased in width and terminating in an outlet leg, the said outlet leg having a top portion which slopes downwardly towards its center and having opposite vertical sides, the draft tube from its inlet to its 80 outlet extremity increasing in area. 85

3. A draft tube comprising an inlet member and an outlet leg with an elbow therebetween, the said elbow being decreased in breadth from the upstream towards the downstream portion thereof by means of an upstream, practically constant radius curve and a downstream easement curve, said easement curve starting at a materially lower elevation than said constant radius curve and the said elbow bend being correspondingly and proportionately increased in width, the outlet leg having a flattened top portion in the form of an inverted arch. 90

4. A draft tube having inlet and outlet extremities with an elbow bend therebetween, the inlet extremity being circular and the tube as an entirety from its inlet extremity being increased in lateral extent and continuing with this lateral increase throughout the elbow in a direction from the upstream towards the downstream portion of said bend, the elbow bend having an upstream, practically constant radius curve and a downstream easement curve, the outlet extremity having a flattened top portion with members converging towards the center from opposite sides of the said outlet extremity. 105

5. A draft tube having inlet and outlet extremities with an elbow bend therebetween, the inlet extremity being circular and the tube as an entirety from its inlet extremity being increased in lateral extent and continuing with this lateral increase through 110 120 125 130

the elbow in a direction from the upstream towards the downstream portion of said bend, the elbow bend having an upstream, practically constant radius curve and a 5 downstream easement curve, the outlet extremity having a flattened top portion with members converging towards the center from opposite sides of the said outlet extremity, the sides of the outlet extremity 10 being vertically straight.

6. A draft tube having inlet and outlet extremities with an elbow bend therebetween and gradually increased in lateral extent from the inlet extremity which is circular in contour to the outlet leg at a distance beyond the termination of the elbow bend, the elbow bend correspondingly and gradually increasing in lateral extent 15 throughout the formation thereof towards the outlet extremity, the elbow bend having an upstream, practically constant radius curve and a downstream easement curve, the elbow bend gradually decreasing in transverse vertical extent towards the outlet 20 extremity, and the outlet extremity having a flattened top which continues with diminishing structure partially into the upper downstream side of the elbow.

7. A draft tube having inlet and outlet 30 extremities with an elbow bend interposed between said extremities and continuous therewith, the said elbow being materially flattened in a transverse vertical direction within the area of the bend from the upstream towards the downstream portion thereof and also increasing in width within 35 the area of the bend and regularly continuing into the outlet extremity, the elbow bend having an upstream, practically constant 40 radius curve and a downstream easement curve of transversely flattened contour in the form of an inverted arch and having vertical sides with fillets in the upper and lower angles of the same.

45 8. A draft tube having inlet and outlet extremities and an elbow bend between the two extremities, the inlet extremity being concentric with relation to a central axis and regularly continuing into the elbow bend, the elbow bend regularly decreasing 50 in breadth by an upstream substantially constant radius curve and a downstream easement curve, differing from the upstream curve, the said bend also positively increasing 55 in width divergently, and said divergence regularly and fully continuing to the outlet extremity of the tube, the outlet extremity of the tube having flattened top and side portions, the flattened top portion of 60 the outlet extremity extending a distance rearwardly into the elbow bend, and the opposite curved sides of the bend merging into straight vertical sides of the said outlet extremity, the said outlet extremity also

having a centrally disposed longitudinally 65 arranged pier therein fully from the top to the bottom of said extremity.

9. A draft tube having inlet and outlet extremities and an elbow bend between the extremities, said elbow bend at the upstream 70 portion having a curve which comes from the vertical to the horizontal in an arc of a circle, and the opposite or downstream portion having an easement curve which is formed in the center with a dip towards and 75 merging into the top of the outlet extremity when it is decreased in height at the center and providing an easement curve with less rapid change of curvature in the center than at the outside portions which continues into 80 the outlet extremity to decrease the breadth of the elbow bend in a direction from the upstream towards the downstream portion of the tube, the latter being proportionately increased in width through the elbow, the 85 outlet extremity being decreased in vertical extent at the center.

10. A draft tube having inlet and outlet extremities and an elbow bend between the extremities, said elbow bend at the upstream 90 portion having a curve which comes from the vertical to the horizontal and the opposite or downstream portion having a curve 95 which is formed with a dip towards and merging into the top of the outlet extremity and providing an easement curve with less rapid change of curvature in the center than at the outside portion and continuing into the outlet extremity to decrease the breadth of the bend in a direction from the upstream 100 towards the downstream portion of the tube and proportionately increase the said width of the tube at the elbow, the outlet extremity being formed with a flattened top portion in the form of an inverted arch 105 having a central longitudinally extending dividing pier which terminates at its inner end at the outer termination of the elbow curve.

11. A draft tube having inlet and outlet 110 extremities with an elbow bend therebetween, the inlet extremity being circular and the tube as an entirety from its inlet extremity being increased in lateral extent and continuing with this lateral increase through the elbow in a direction from the upstream towards the downstream portion of said bend, the elbow bend having an upstream, practically constant radius curve and a 120 downstream easement curve, the outlet extremity having a transversely straight flattened top portion from one side to the other and also provided with an upward flare, the sides of the outlet extremity being vertically straight.

12. A draft tube having inlet and outlet extremities with an elbow bend interposed between said extremities and continuous

therewith, the said elbow being materially flattened in a transverse vertical direction within the area of the bend portion thereof and also increasing in width within the area 5 of the bend and regularly continuing into the outlet extremity, the elbow bend having an upstream, practically constant radius

curve and a downstream easement curve of flattened contour which is transversely straight and having vertical sides with fillets ¹⁰ in the upper and lower angles of the same.

In testimony whereof I have hereunto set my hand.

GEORGE A. JESSOP.
